Term of patent 14 years

Int. Cl. D12—99

U.S. Cl. D71—1 S

FIG. 1

FIG. 2

FIG. 3

FIG. 1 is a perspective view of the traversing hanger for personnel sling showing my new design;

FIG. 2 is an enlarged front view of the traversing hanger; and

FIG. 3 is an enlarged top view thereof.

The traversing hanger for personnel sling is shown in full lines in the drawing and a personnel sling supported by the hanger is shown in broken lines in FIG. 1 for illustrative purposes only. The hanger is used for traversing the spinnaker pole of a sailboat.

I claim:

The ornamental design for a traversing hanger for personnel sling, as shown and described.
